EYEGLASS LENS

Robert Passet, Vincennes, France, assignor to Societe Industrielle de Lunetterie, Paris, France

Application February 1, 1954, Serial No. 28,751

Term of patent 14 years

(Cl. D57—1)

To all whom it may concern:

Be it known that I, Robert Passet, a citizen of France, residing at Vincennes (Seine), France, have invented a new, original, and ornamental design for Eyeglass Lens, of which the following is a specification, reference being had to the accompanying drawings, forming part thereof.

Figure 1 is a side elevation, and

Figure 2 is a front elevation of my novel design for eyeglass lens.

I claim:

The ornamental design for eyeglass lens, as shown.
